United States Patent Office.

HIRAM THOMPSON, OF WORCESTER, MASSACHUSETTS, ASSIGNOR TO R. BALL & CO., OF SAME PLACE.

Letters Patent No. 98,124, dated December 21, 1869.

IMPROVEMENT IN CUTTER-HEAD.

The Schedule referred to in these Letters Patent and making part of the same.

To all whom it may concern:

Be it known that I, HIRAM THOMPSON, of the city and county of Worcester, and Commonwealth of Massachusetts, have invented certain new and useful Improvements in Cutter-Heads for shaping and moulding-machines, and for other similar purposes; and I do hereby declare that the following is a full, clear, and exact description of the same, reference being had to the accompanying drawings, forming a part of this specification, in which—

Figure 1 represents a perspective view of my improved cutter-head, together with a portion of the spindle or shaft to which it is attached;

Figure 2 represents a longitudinal section of the same; and

Figure 3 represents a cross-section.

To enable those skilled in the art to which my invention belongs to make and use same, I will proceed to describe it more in detail.

The nature of my invention consists—

Frist, in an improved frame for holding the cutters, as will be hereafter explained; and

Second, in the combination, with the end of the spindle or shaft, of the cutter-frame, tightening-wedge, screw-nut, and supporting flanges, as will be hereafter described.

In the drawings—

A is the spindle or shaft, which may be supported in suitable bearings, so as to turn in a vertical or horizontal position, as may be preferred.

B is a collar or flange, which may be formed, or swaged up, or shrink upon the end of the spindle A.

The base C of the cutter-frame D is provided with a hole, through which the end of the spindle A is passed, as shown in the drawings.

The other end of the cutter-frame D is provided with a larger hole, to receive the cylindrical portion of the tubular tightening-wedge E, while the outer end of the spindle A is provided with a screw-thread, *a*, to receive the thread of the tightening-nut F.

The cutters G G are bevelled off at their ends, to fit the bevel recesses *b b*, in the base of the cutter-frame C, and the bevelled sides *c c* of the tightening-wedge E.

The base of the cutter-frame is connected to the top or outer end H of the frame, by two supporting-bars, I I, having plain inner surfaces and curved or circular outer surfaces, as indicated in the drawings.

The cutters G G are inserted so as to rest against the insides of the supporting-bars I I, with their bevelled end resting in the small recesses *b b*, and the tightening tubular wedge is inserted so as to force the cutters against the base C, and also against the inner sides of the supporting-bars I I.

The tubular tightening-wedge, being forced firmly against the ends of the cutters G G, by means of the nut F, while the base C is supported by means of the flange or collar B, which is secured, as before explained, to the spindle A.

From the foregoing description, it will be seen that cutters of different widths may be secured in the frame D, by means of the tubular tightening-wedge E and nut F, by simply screwing the nut F further in or out, so as to bring the bevelled edges *c c* of the tightening-wedge E against the bevelled ends of the cutters, whether wide or narrow.

It will be observed that the cutter-frame D is open upon each side, thus making my cutter-head light, while at the same time possessing great strength and ease of adjustability to receive and hold cutters of different widths.

Having described my improved cutter-head,

What I claim therein as new, and of my invention, and desire to secure by Letters Patent, is—

1. The cutter-frame D, made with the recessed base C, holding-bars I I, and open end or top H, for the reception of the tightening-wedge E, substantially as shown and described.

2. The combination, with the spindle A, provided with the collar or shoulder B, screw-thread *a*, and nut F, of the cutter-frame D and tightening tubular wedge E, substantially as and for the purposes set forth.

HIRAM THOMPSON.
